UNITED STATES PATENT OFFICE.

WILLIAM H. NIEMEYER, OF BALTIMORE, MARYLAND.

BOTTLE CAP OR CLOSURE.

No. 872,672.

Specification of Letters Patent.

Patented Dec. 3, 1907.

Application filed March 18, 1907. Serial No. 363,143.

To all whom it may concern:

Be it known that I, WILLIAM H. NIEMEYER, a citizen of the United States, residing at Baltimore, in the State of Maryland, 5 have invented certain new and useful Improvements in Bottle Caps or Closures, of which the following is a specification.

This invention relates to improvements in bottle caps or closures, and the object is to 10 provide a metal cap of the type having a peripheral flange to be tucked or pressed in under the bead of the bottle or jar, so constructed that the flange thereof will readily accommodate itself to the slight variance in 15 size in the bottle beads without breaking or splitting in such a manner as to destroy its effectiveness as a seal.

With the above object in view, the invention consists in the novel features of construction hereinafter fully described, particularly pointed out in the claims, and clearly illustrated by the accompanying drawing, in which

Figure 1 is a sectional view of a cap constructed in accordance with my invention, taken in the line $x-x$ of Fig. 2; Fig. 2, an elevation of the cap; Fig. 3, a sectional view on the line $y-y$ of Fig. 1, and Fig. 4, a sectional view of the cap in position closing the 30 mouth of the bottle.

Heretofore metal caps have been provided for sealing bottles, said caps having continuous flanges, the lower portions of which are tucked or pressed in under the bead of the 35 bottle. The beads of bottles vary slightly in size, that is, in circumference, with the result that if either smaller or larger than the internal diameter of the flange of the cap, the latter will break or split when pressed in 40 under the former, in such manner as to prevent a perfect seal. I obviate this objection by providing the flange at intervals about its circumference with thin web-portions of such slight thickness that the metal at this 45 point will break should the bead be either larger or smaller. The vertical extent of this break, however, is limited so that it cannot extend upward a sufficient distance to destroy the effectiveness of the seal. Should 50 the bead be smaller, these thin web-portions

by breaking prevent puckering of the flange by reason of the superfluous metal and permit the separated portions of the flange to be tightly tucked in under the bead of the bottle.

Referring now more particularly to the drawing, 1 designates the cap having the depending flange 2. This flange is provided at intervals about its circumference with perforations 3, which are placed a sufficient distance below the top of the cap to prevent any danger of interfering with a perfect seal. Extending from the lower edge of the flange, on the inner and outer side thereof, and terminating at the perforations 3, are substantially V-shaped grooves of such depth as to leave a thin wall or web portion 4. Thus the flange is formed of a plurality of depending portions connected by thin web-portions 4.

As shown in Fig. 4, the metal cap is secured upon the bottle by pressing in the flange under the bead, at several points about its circumference, the usual cork disk 5 being placed on the inside of the cap.

Having thus fully described my invention, 75 what I claim as new, and desire to secure by Letters Patent of the United States, is;—

1. A bottle sealing cap having a top and a continuous flange integral therewith formed about its circumference with a plurality of 80 spaced perforations and thin web-portions extending from the edge thereof to said perforations.

2. A bottle sealing cap having a top and a continuous flange integral therewith formed 85 at intervals about its circumference with thin web-portions extending upward from the edge thereof and perforations in which said thin portions terminate, said perforations being disposed a sufficient distance below the top of the cap to be below the upper edge of the bottle top when the cap is in position thereon.

3. A bottle sealing cap having a top and a continuous flange integral therewith formed 95 about its circumference with spaced perforations and having the metal thereof removed on its inner and outer surfaces to form thin web-portions which extend from the lower edge thereof to said perforations.

4. A bottle sealing cap having a top and a continuous flange integral therewith and formed about its circumference with spaced perforations and having alined V-shaped 5 grooves in its inner and outer surfaces extending from its lower edge to said perforations and of such depth as to form thin web portions.

In testimony whereof I affix my signature in presence of two witnesses.
